UNITED STATES PATENT OFFICE.

VICTOR M. OSBORN, OF LA FAYETTE, INDIANA.

FLYING-MACHINE.

1,076,514.

Specification of Letters Patent.

Patented Oct. 21, 1913.

Application filed February 4, 1913. Serial No. 746,229.

To all whom it may concern:

Be it known that I, VICTOR M. OSBORN, a citizen of the United States, residing at La Fayette, in the county of Tippecanoe and State of Indiana, have invented new and useful Improvements in Flying-Machines, of which the following is a specification.

This invention relates to flying machines of the heavier-than-air type, the object of the invention being to provide a machine which is inherently stable and which embodies important and desirable safety factors, as hereinafter fully described and claimed.

15 In the accompanying drawings, for purposes of illustration, I have shown the application of my invention to a monoplane type of machine, although it is to be understood that the essential features thereof may 20 be embodied in biplane or other multiplane machines.

In the said drawings: Figure 1 is a side elevation of the machine. Fig. 2 is a front elevation thereof. Fig. 3 is a vertical transverse section on line 3—3 of Fig. 1. Fig. 4 is a sectional plan view on line 4—4 of Fig. 1. Fig. 5 is a perspective view of the main portion of the car or main frame and the supporting surface separated from each 30 other and showing more clearly the pivotal connections.

In carrying my invention into practice I provide a machine body including a main frame or car 1, which carries the supporting surface 2. The said main frame or car 1 includes a substantially triangular base formed of rods or tubes 3 and provided with suitably cushioned launching and landing wheels 4. This base is provided with a longitudinally extending bed or platform 5 supporting the driving motor 6, the aviator's seat 7, and steering and controlling devices 8 and 9, which elements are arranged in a novel manner, as hereinafter fully described. The main frame also carries a head extension or frame portion 10 and a tail frame or extension 11. The portion 10 is provided with bearings for a longitudinally extending shaft 12 carrying a tractor propeller 13, which shaft is driven by chain or other suitable gearing 14 from the shaft of the motor 6. The tail frame or extension 11 has mounted thereon a vertical rudder 15 suitably coupled to the steering and controlling device 8, whereby said rudder may be

adjusted to steer the machine laterally in the usual way.

The body of the car or main frame is substantially of frusto-pyramidal form, and includes inverted V-shaped side standards 60 forming with the associated rods or tubes 3 triangular frame portions of maximum strength and durability, said frame portions being connected to each other and to the base by suitable uprights 17 and braces 18. 65 The supporting surface 2 comprises, as shown in the present instance, a plane of any suitable construction, the wings 19 and 20 of which are preferably inclined at a slight dihedral angle. This plane is provided with ribs 21 and is fixed to an inverted V-shaped frame 22 which extends through the plane. The upper portion of the frame 22 forms a truss bracket 23, between which and the wings extend upper 70 truss wires or cables 24, while the lower or diverging arms of the frame extend downwardly on opposite sides of the main frame and are connected at their lower ends by a cross rod 25. A lower set of said wires or 75 cables 26 connect these arms of the frame 22 with the wings 19 and 20, the outer ends of the wires or cables being preferably fastened to the ribs 21, as shown, whereby the frame and wings are rigidly united. 85

The cross rod 25 extends transversely through the main frame below the bed or platform 5, and the supporting surface 2 is connected with the upper extremities of the uprights of the main frame by hinges or 90 pivots 26^a, whereby the body of the machine and the supporting surface are pivotally coupled for relative fore and aft swinging movements. The rod or cross piece 25 is connected by a link 27 with the controlling 95 device 9, which is shown in the form of a lever movable in a fore and aft direction and provided with a spring actuated dog or pawl 28 to engage a rack 29 on the car, whereby the machine body and supporting 100 surface may be relatively adjusted and locked whenever desired against relative movement.

It will be observed that the motor 6 is mounted upon the base of the car or body 105 at a point in advance of the aviator's seat and of the centers of gravity and pressure, while the aviator's seat and controlling devices are mounted upon the base of the car at a point in rear of the motor and of the 110

centers of gravity and pressure, whereby the respective weights mentioned are employed to counterbalance each other to a determined extent, the prepondering part of the 5 weight of the motor being sufficient to balance the weight of the tail frame, whereby a high degree of inherent fore and aft stability is secured. At the same time a low center of gravity is obtained, which adapts 10 the car or body to operate as a pendulum, tending to maintain both longitudinal and lateral stability against excess air pressures liable to disturb the poise of the machine. The described arrangement of the motor is 15 also of advantage in that it enables the aviator to have ready access thereto and maintain a constant observation of the working thereof, while at the same time avoiding liability of injury to the aviator from the 20 downward plunge of the motor in the event of the fall of the machine, which is liable to occur in all machine structures where the motor is arranged above or in rear of the aviator's seat.

25 It will be observed that in the flight of the machine the aviator by means of the controlling device 9 may tilt the supporting surface either to vary its angle of incidence, and lifting power, or to adapt it to serve as 30 an elevator or horizontal rudder to steer the machine up or down in a vertical plane, or to restore the longitudinal balance of the machine in the event of its longitudinal stability being at any time disturbed. The control 35 device may be unlatched in order to allow a relative pivotal balancing motion between the machine body and supporting surface at times desired or may be locked against movement to hold the supporting surface 40 fixed at any required working angle. It will be observed also that by the described construction of the frame and supporting surface, the car is maintained at all times in a substantially horizontal plane, whether the 45 machine is traveling straight ahead, ascending or descending, while the propeller as a consequence always has a fixed path of rotation. Hence as the angle of travel of the propeller is not varied when the path of 50 travel of the machine is changed, as in steering upward or downward, the tendency of

the propeller to exert its gyroscopic force and throwing excess strain upon either wing of the machine is avoided.

55

I claim:—

1. A flying machine including a main frame of approximately frusto-pyramidal form, a car or platform carried by said main frame, a similarly shaped independent frame pivotally connected with the vortex of said 60 main frame for relative longitudinal tilting motion on a horizontal transverse axis, said independent frame extending above the main frame and beneath the car or platform, and wings fixed to the independent frame 65 and mounted to tilt therewith, the said main frame and car forming a gravity controlled body operating by gravity to maintain a normal perpendicular position, and means for tilting said independent frame upon the 70 body and holding it in tilted position.

2. A flying machine including a body, formed of a main frame having a base and uprights rising therefrom, said main frame having a head portion carrying a tractor 75 propeller and a tail extension provided with a vertical rudder, a motor mounted upon the base in advance of the centers of gravity and pressure and in gear with the propeller, an aviator's seat mounted upon the base 80 in rear of the centers of gravity and pressure, a controlling device upon the body for adjusting the vertical rudder, a supporting surface having a frame including side members extending down on opposite sides of the 85 main frame and a cross piece connecting said side members and extending transversely of the main frame, said supporting surface being pivoted for a relative fore and aft motion to the uprights of the body, 90 a controlling device upon the base of the body in proximity to the aviator's seat, a connection between the same and the cross piece of the frame of the supporting surface, and means for locking said controlling device in adjusted position. 95

In testimony whereof I affix my signature in presence of two witnesses.

VICTOR M. OSBORN.
